(57) **CLAIM**

We claim, the ornamental design for a confection, as shown and described.

DESCRIPTION

FIG. 1 is a perspective view of a confection, showing a first embodiment of our new design;

FIG. 2 is a front elevation view of the embodiment shown in FIG. 1;

FIG. 3 is a back elevation view of the embodiment shown in FIG. 1;

FIG. 4 is a side elevation view of the embodiment shown in FIG. 1;

FIG. 5 is a another side elevation view of the embodiment shown in FIG. 1;

FIG. 6 is a top plan view of the embodiment shown in FIG. 1;

FIG. 7 is a bottom plan view of the embodiment shown in FIG. 1;

FIG. 8 is a perspective view of a confection, showing a second embodiment of our new design;

FIG. 9 is a front elevation view of the embodiment shown in FIG. 8;

FIG. 10 is a back elevation view of the embodiment shown in FIG. 8;

FIG. 11 is a side elevation view of the embodiment shown in FIG. 8;

FIG. 12 is a another side elevation view of the embodiment shown in FIG. 8;

FIG. 13 is a top plan view of the embodiment shown in FIG. 8; and,

FIG. 14 is a bottom plan view of the embodiment shown in FIG. 8.

The broken lines in FIGS. 8–14 illustrate portions of the confection that form no part of the claimed design.
